MUSICAL PRACTICE TIMER

Peter F. D. Jansen, Santa Monica, Calif.

Application November 7, 1949, Serial No. 5,924

Term of patent 7 years

(Cl. D56—1)

To all whom it may concern:

Be it known that I, Peter F. D. Jansen, a citizen of the United States and resident of the city of Santa Monica, county of Los Angeles, State of California, have invented a new, original, and ornamental Design for a Musical Practice Timer of which the following is a specification, reference being had to the accompanying drawing, forming a part hereof, in which:

Fig. 1 is a front elevational view of a musical practice timer, showing my new design;

Fig. 2 is a rear elevational view;

Fig. 3 is a top plan view;

Fig. 4 is a bottom plan view;

Fig. 5 is a perspective; and

Fig. 6 is an end elevational view thereof.

I claim:

The ornamental design for a musical practice timer, substantially as shown.

PETER F. D. JANSEN.
